NICHOLAS TROISI, OF NEW YORK, N. Y.

IRONING MACHINE

Application filed December 7, 1928. Serial No. 324,422.

My invention relates to a new and improved ironing machine.

One of the objects of my invention is to provide an ironing machine which is especially adapted for ironing the seam portions of garments, such as sleeves and the like.

Another object of my invention is to provide an ironing machine especially adapted for this purpose employing improved means 10 for supplying moisture to the part to be ironed.

Another object of my invention is to provide a simple machine which can be readily used by inexperienced operators.

15 Another object of my invention is to provide a machine which can be conveniently set so as to permit the introduction of a fresh piece of work to be ironed.

Other objects of my invention will be set 20 forth in the following description and drawings which illustrate a preferred embodiment thereof, it being understood that the above general statement of the objects of my invention is intended merely to generally explain 25 the same and not to limit it in any manner.

Fig. 1 is a side elevation.

Fig. 2 is a plan view.

Fig. 3 is a sectional view along the line 3—3 of Fig. 2.

30 Fig. 4 is a sectional view on the line 4—4 of Fig. 1.

Fig. 5 is a sectional view on the line 5—5 of Fig. 1.

Fig. 6 is a diagrammatic view of the 35 circuit of the motor and the electric iron.

The machine has a frame 1 on the underside of which there is a treadle 2 having a rope 3 passing around pulley 4. Rope 3 actuates lever 5 pivoted to the frame of the 40 machine at 6. The machine is provided with a narrow work-table 7 which forms part of the frame of the machine. A belt 8 passes over the table. The belt 8 has an upper run and a lower run which pass over a front pulley 9 and a rear pulley 10. The rear pulley 10 is on the shaft of an electric motor M. The electric motor M is provided with a starting box 12 having the usual switch-arm 45 14. The switch-arm can either be actuated by hand, or by means of a treadle 15 which is

connected to the switch-arm 14 by means of a rod 16. The switch-arm 14 is provided with the usual spring (not shown in the drawings) to keep it in the upper and inoperative position.

55 The flatiron 19 is preferably heated by means of an electric heating coil 19^a diagrammatically shown in Fig. 6. As shown in Fig. 6, it is preferable to have the motor circuit and the circuit of the heating coil 19^a, controlled by the switch-arm 14. For this purpose the heating coil 19^a and the motor M are connected in series. Hence when the arm 14 is in the upper position, no current is supplied to either the motor or the flatiron.

60 Likewise, increased current is simultaneously supplied to the motor M and to the heating coil 19^a. A safety-switch 17 is provided for cutting off the supply of current. When it is desired to start the operation of 70 the machine, the motor M can be operated without feeding any work to the machine, until the flatiron 19 has been raised to the proper temperature.

65 As shown in Fig. 6, the heating coil 19^a of the flatiron may be supplied with a variable shunt. Hence if the current which passes through the motor is too high, the heating coil of the flatiron can be protected by the use of the shunt 19^b.

75 The flatiron 19 is connected to or integral with the collar 20 which is also connected to or integral with the water-pot 21. The water pot 21 has a filling spout 22. Wicks 23 protrude from the pot 21, the supply of water 80 to said wicks being controlled by a valve 24. These wicks press upon a roller 25 whose outer surface is made of some absorbent material such as suitable cloth, felt, or the like. If the wicks 23 were caused to directly contact 85 with the portion of the fabric article to be moistened, it would be difficult to secure sufficient pressure of said wicks against the article, because said wicks, being made of soft absorbent material, are necessarily yielding. 90 However, the wicks merely serve to supply moisture to the absorbent material on the periphery of the moistening roller 25. Hence, the roller 25 can be forced with greater pressure against the work than if ordinary wicks 95 100

- directly contacted with the work. While I prefer to use a roller, I do not wish to be limited to a turnable moistening device, or to a moistening device having a rigid core, since it would be an equivalent to utilize a moistening device comprising absorbent material solely and directly applied to the work, and having greater rigidity than the ordinary wick or sponge. It has been proposed to 10 fine a wick or sponge in a metal tube or chamber, but, in order to practically use such a device with any substantial pressure, it was necessary to cause the edge of said tube or chamber to contact with the work, which is 15 highly undesirable when there is a relative movement between the work and the moistening device. According to my invention, the absorbent material alone is applied to the work.
- 20 The trunnions of the roller 25 are connected upon a frame-piece 26 which is either integral with or connected to the collar 20. The roller 25 is pressed upon the belt 8 or upon a piece of cloth located upon the belt 8 with only 25 sufficient force to moisten the work. It is preferable to make the arm 26 springy or resilient so that the moistening device can be pressed down on the work with any desired force, in front of the iron 19.
- 30 The flatiron and pot are given a vertical up and down movement by means of a pair of arms 27 pivotally connected to the pot 28 and a second pair of arms 27^a pivotally connected to the collar 28^a.
- 35 The arms 27 are pivotally connected at 29 to a frame projection 30 which remains fixed. The arms 27^a are pivotally connected at 29^a to the frame. The pair of arms 27, and the pair of arms 27^a provide a parallel motion 40 whereby the flatiron 19 and the water-pot, etc. are moved up and down vertically. A tension spring 31 tends to force the flatiron 19 downwardly with sufficient pressure. The upper end of this tension spring 31 is connected to the member 33 which forms a bell-crank extension of one of the arms 27^a. The lower end of the spring 31 is connected to the frame of the machine. Upon actuating the lever 5, additional force can be exerted upon 45 the associated lever 27^a to supply additional pressure to the flatiron. It will be noted that the arms 27 and 27^a constitute a parallel motion device whereby the flatiron 19 is moved towards the work-table and away therefrom 50 while its underside remains substantially horizontal.
- When the pot is raised by the hand-hold 55 32, the member 33 is moved beyond the vertical position, so that the tension spring 31 then acts to upwardly throw the flatiron and keep it in the upper position. The line of action of the tension spring 31 is close to the pivot point 29 so that a very slight raising of the arms 27^a in unison with arms 27 is 60 sufficient to throw the line of action of the

tension spring 31 to the other side of the pivot point 29 to then move the water-pot, iron and associated parts upwardly.

The operation of the device is as follows:

The operator upwardly pushes the hand-hold 32 so that the spring 31 operates to upwardly turn the arms 27 and the arms 27^a, so that the flatiron 19, the water-pot 21, and the parts associated therewith are moved upwardly and held in the upper position. The operator then introduces any suitable part of a garment, such as a sleeve S, over the narrow table 7 so that the upper part of the sleeve containing the seam is acted upon by the flatiron 19.

As shown in Fig. 5, the front end of the table 7 is provided with a plate 7^a made of any smooth metal.

The upper run of the belt 8 fits in a suitable groove in the said top plate 7^a. The sleeve S is fed by the upper run of the belt 8, in the position shown in Fig. 5, so that said sleeve passes over the front part of the table 7, while it is fed forwardly. The seam of the sleeve is pressed by the iron 19. Any suitable stop or the like can be provided for limiting the downward movement of the iron 19, to regulate its bottom position so that it cannot be pressed too forcibly upon the sleeve S, which would prevent the seam from being fed by the upper run of the belt 8. Likewise, and as shown in Fig. 5, the iron 19 is wider than the belt 8, and said iron 19 is also wider than the groove in the top plate 7^a. This construction acts as an automatic stop to limit the pressure with which the iron may be applied to the seam, because if the iron is pressed down too hard, it contacts with the unrecessed portion of the top plate 7^a.

The operator can then press upon the treadle 2 so as to move the bell-crank extension 33 to the position shown in Fig. 1. The belt now operates to forwardly feed the article to be ironed, this being suitably moistened by the roller 25, upon the seam thereof, before it is acted upon by the hot flatiron 19. While the article is being ironed, the operator can press upon the treadle 2 to supply additional pressure to the flatiron. After the article has been ironed, the operator pushes upwardly upon the hand-hold 32 so as to raise the flatiron and the associated parts. If desired, the same article can be ironed two or more times. Likewise, the operation of the motor can be stopped at any time by merely releasing the control treadle 15 which is directly adjacent the pressure treadle 2.

The belt 8 can be made of canvas or other material provided with a rough surface, or with suitable projections so that it will positively grip the underside of the sleeve or the like, and feed it forwardly. Since the underside of the flatiron is smooth, the pressure of the flatiron will offer little or no frictional resistance to the movement of the article S,

which is produced by the upper run of the belt 8. It is not intended that the spring 31 should cause the flatiron 19 to press with considerable force upon the work. This pressure would ordinarily be applied by the hand of the operator, exerted upon the member 32, or by means of the treadle 2. The operator will readily learn the proper pressure to be applied upon the work. It is likewise clear that the operator can manipulate the member 32, so as to intermittently apply the flatiron 19 with the necessary pressure to the work.

10 While I have shown a complete operative machine, certain of the sub-combinations shown therein could be used independently of the other parts in the complete machine illustrated.

15 Likewise, while I have shown the ironing device 19 and the moistening device 25 being operated simultaneously, it is not necessary to operate them during precisely the same interval as long as the moistening device is moved away from the work-table when the ironing device is moved away by manipulation of any suitable part.

20 25 I have shown a preferred embodiment of my invention, but it is clear that numerous changes and additions can be made without departing from the spirit of my invention.

30 I claim:

1. In an ironing machine, the sub-combination of a work-table, an ironing device associated with said work-table, said ironing device being movable towards said work-table and away therefrom, moistening means comprising a water receptacle which is movable towards and away from said work-table simultaneously with said ironing device, said moistening means including an absorbent moistening member having a rigid core, said moistening member being connected with said water receptacle, and being movable in unison with said ironing device so that said moistening member contacts with and feeds moisture to the work only when said ironing device is pressed against the work, means adapted to urge said moistening member against the work, and feeding means adapted to feed the work along said work-table, said moistening member projecting in front of the iron so that the work is moistened before it is ironed.

2. In an ironing machine, a work-table, an ironing device movably mounted with respect to said work-table, means adapted to actuate said ironing device toward said work-table and away therefrom, and a moistening device for the work comprising a turnable moistening wheel having a rigid core and an outer absorbent face, and means adapted to urge said moistening device against the work to be ironed.

3. In an ironing machine, a work-table, an ironing device movably mounted with respect to said work-table, means adapted to actuate

said ironing device towards said work-table and away therefrom, and a moistening device for the work having a rigid core and an outer absorbent face, and means adapted to urge said moistening device against the work to be ironed.

4. In an ironing machine, the subcombination of a work-table, an ironing device connected to a water receptacle, a moistening member also connected to said water receptacle, means adapted to lead moisture from said water receptacle to said moistening member, and means adapted to operate the before-mentioned parts in unison towards and away from said work-table, said means including a pivoted arm having a tension spring associated therewith, said tension spring being adapted to urge the said ironing device and its associated parts towards said work-table, the line of action of said tension spring being sufficiently close to the pivot of said arm to cause said tension spring to upwardly hold the before mentioned parts when they are raised a short distance.

5. In an ironing machine, a work-table, an endless belt associated therewith and adapted to feed an article over said work-table, means adapted to actuate said belt, an ironing device movably mounted above said work-table, a water receptacle connected to said ironing device and movable therewith, a moistening wheel connected to said water receptacle and movable therewith, wick means connecting said moistening wheel to said water receptacle, a parallel motion device adapted to raise and lower the said ironing device and its associated parts, a tension spring associated with said parallel motion device, and having its upper end connected to an upwardly directed arm connected to said parallel motion device, said tension spring being adapted to downwardly force said ironing device in one of its positions and being adapted to hold said ironing device above said work-table in another position thereof, and additional mechanism adapted to downwardly press the ironing device upon the work-table.

6. In an ironing machine, a work-table, an endless belt associated therewith and adapted to feed an article over said work-table, means adapted to actuate said belt, an ironing device movably mounted above said work-table, a water receptacle connected to said ironing device and movable therewith, a moistening wheel connected to said water receptacle and movable therewith, wick means connecting said moistening wheel to said water receptacle, a parallel motion device adapted to raise and lower the said ironing device and its associated parts, a tension spring associated with said parallel motion device, and having its upper end connected to an upwardly directed arm connected to said parallel motion device, said tension spring

being adapted to downwardly force said ironing device in one of its positions and being adapted to hold said ironing device above said work-table in another position thereof, and
5 additional mechanism adapted to downwardly press the ironing device upon the work-table, said additional mechanism being operable by a treadle and the means for actuating said belt being controllable by a second treadle adjacent to the first mentioned
10 treadle.

7. In an ironing machine, a work-table having a work-plate at the top thereof, said work-plate having a recess in its top surface,
15 and an endless feeding device having an upper run located in and adapted to move in the recess of said work-plate, and a vertically movable pressing device located above the recess of said work-plate, said pressing device
20 being wider than said recess, so that said pressing device extends laterally beyond said recess.

In testimony whereof I affix my signature.
NICHOLAS TROISI.
